UNITED STATES PATENT OFFICE

EDWARD WUENN, OF CHICAGO, ILLINOIS

DESIGN FOR A RADIOCABINET

Application filed February 15, 1930. Serial No. 34,568. Term of patent 3½ years.

To all whom it may concern:

Be it known that I, EDWARD WUENN, a citizen of the United States, residing in Chicago, Cook County, Illinois, have invented a new, original, and ornamental Design for a Radiocabinet, of which the following is a specification, reference being had to the accompanying drawing, forming a part hereof.

The single figure of the drawing is a perspective of a radiocabinet in accordance with this design.

I claim:

The ornamental design for a radiocabinet substantially as shown.

EDWARD WUENN.
